UNITED STATES PATENT OFFICE.

JOSÉ RICARDO ELIZONDO, OF NEW YORK, N. Y.

ATTACHMENT FOR COMBINING COLLARS AND TIES.

1,833,398.

Specification of Letters Patent.

Patented Mar. 9, 1920.

Application filed November 20, 1918. Serial No. 263,342.

To all whom it may concern:

Be it known that I, JOSÉ R. ELIZONDO, a citizen of the Republic of Mexico, and a resident of the city of New York, borough 5 of Manhattan, and county and State of New York, have invented a new and Improved Attachment for Combining Collars and Ties, of which the following is a full, clear, and exact description.

10 This invention relates to wearing apparel and has particular reference to collars and ties such as are commonly worn by men.

Among the objects of the invention is to provide a device for combining the collar and the necktie that will allow the application of the combined collar and tie to the shirt at the same time; that will economize not only in tie material but in the durability of the tie, and that will provide means 20 for supporting any standard or approved type or design of necktie.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a front view of a collar adapted for my purposes.

35 Fig. 2 is a detail view in front elevation of the locking tongue portion of the collar having the tie holding clips fixed thereto.

Fig. 3 is a similar view indicating the next succeeding step in which the tie is 40 placed upon the clips.

Fig. 4 is a plan view of a blank from which a clip is made.

Fig. 5 is a detail perspective view of one of said clips.

45 Fig. 6 is a vertical sectional detail on the line 6—6 of Fig. 2 showing the relation of the shank portion of the clip to the collar.

Fig. 7 represents the application of a bow tie to one of my improved collars.

50 Fig. 8 is a detail perspective view of one type of jack or holder upon which a tie is formed or tied, preliminary to the application thereof to the clips.

Fig. 9 is a view of the same character as Fig. 2 and indicating a modification of an attachment device.

Figs. 10 and 11 are perspective detail views of the form of attachment device shown in Fig. 9 respectively in the locked and unlocked positions.

60

Fig. 12 is a vertical sectional view on the line 12—12 of Fig. 9; and

Fig. 13 is a modified form of jack showing the manner of supporting it against a wall or the like and indicating the fingers 65 as in the form of pins.

Referring now more particularly to the drawings I show a collar 10 of any conventional or approved design as to its general appearance including a locking tongue 11. 70

This collar is shown provided with a pair of holes or slots 12 disposed one above the other at any convenient place between the usual collar buttonhole 13 and the extreme end of the locking tongue. These features 75

12 are preferably formed as horizontal parallel slots. 14 indicates similar slots formed in the same ply of the collar as the tongue and arranged at the same elevation as the slots 12 and as far as the opposite 80

side of the buttonhole 13. That is to say, the slots 12 and 14 are arranged in similar pairs and symmetrically disposed with respect to the buttonhole. These slots 12 and 85

14 may be variously formed or constructed 85 and constitute holding means for the clips that support the tie. For simplicity and durability they are preferably formed in the inner ply of the collar during the manufacture thereof and may be finished the same 90

as ordinary buttonholes.

The clips above referred to are indicated at 15 and may be formed in various ways and of any suitable material such as sheet metal, celluloid or the like, each comprising 95

a shank 16, a pair of lugs 17, and a hook 18 preferably cut or stamped from a single flat piece of material as in Fig. 4, the tongue being bent down toward or upon the shank 16 around the bending line 19 and then bent 100

upward upon itself at about its middle at 20 bringing the upper or point portion of the hook at about the level of the bending line 19 below the lugs 17. Each clip is so designed and proportioned as to have its 105

shank 16 slipped into or fitted in a pair of slots 12 and 14 where it will be held from displacement by means of friction and also by the grip of the back portion of the hook 18 in co-operation with the shank. 110 These clips obviously may be slipped easily into the place indicated in Figs. 2

and 3 while the operator holds the collar in his hands.

The necktie is made up to embody two short loops 21 irrespective of the style in which the tie is made either as a four-in-hand as in Fig. 3 or as a bow shown in Fig. 7. As a simple and effective means for so tying or making up the tie I recommend the use of a holder or jack comprising a base 22 upon which are fixed a pair of upwardly projecting fingers or hooks 23 spaced from each other a distance equal to the space between the pairs of slots 12 and 14 or the hooks to be supported therein. This jack may be fixed to any stationary object such as a window frame or the like and so may always be in position for operation, in fact it may serve in some cases as a hanger for a razor strop or other devices. In view of the fact that the necktie is not passed around the collar the length thereof may be materially less than in the usual design of the neck tie, hence with the adoption of this system for collars and ties a great saving in material may be effected. Furthermore since a great deal of the wear and tear upon a necktie in the old system is incident to the friction thereof within the collar especially at the back, the life of the tie with this new system is materially prolonged. Again, a necktie can be made up usually much neater and prettier on a jack such as indicated than it can on the wearer's neck before a mirror. The operator has a better vision and better control of the tie under these conditions and when the tie is thus made up with the two loops 21 it may be retained in a definite position or form without remaking or retying for any desired length of time, constituting another feature of advantage because with many ties it is difficult to remake them so as to look as neat as when first tied.

From what has been stated above the method of operation will be readily appreciated as follows: The operator applies a pair of the clips to the respective pairs of holes 12 and 14 on a clean collar before attaching the collar to his shirt, the loops 21 of the tie are then slipped into the hooks 18 of the clips so as to occupy the position shown in Fig. 3. The clips are so held in place in the collar that they will remain in place and hold the tie in place whether the collar is applied to the neck or not. The next step then is for the operator to apply the collar in the usual manner passing first the buttonhole 24 over the back button and then the hole 25 over the front button 26, next the hole 13 over the button 26, and finally inserting the locking tongue 11 into locking position carrying with it that loop 21 supported at the holes 12. Since the holes 12 and 14 are symmetrically arranged with respect to the vertical line passing through the hole 13 and the loops 21 natu-

rally are formed of equal length, no special effort is required on the part of the operator to insure that the necktie will be located and held in a neat central position.

If the same collar is to be worn a second time obviously the collar may be removed from the neck in the usual manner by first slipping out the locking tongue and unbuttoning the collar in the usual manner without removing the tie from the two loops and it will be ready then to be put on again. When, however, the tie or a different tie is to be applied to another collar it may be readily done by applying the clips or another pair of clips to the next collar with a repetition of the steps heretofore set forth.

That form of clip or attachment device shown in sheet 2 of the drawings and indicated as a whole at 27 comprises a tubular shank 28 through which a double-headed pin projects for the purpose of locking the device in place on the inner ply or tongue of the collar 10. As in the other form of the invention the two devices 27 are secured to the tongue end of the inner ply of the collar on opposite sides of the buttonhole 13 and far enough above the level of the buttonhole to hold the tie at the proper elevation. Each clip 27 comprises a hanger 30 constituting a substantially flat extension of the inner end of the tubular shank, and this hanger is bent upward parallel to itself forming a keeper 31 extending above the level of the shank and pin. This keeper is slightly bowed and has its upper end or point bearing against or close to the outer surface of the tongue 11.

The jack comprises a plate 22' of any suitable structure such as a piece of flat metal. This is provided at its center with an indicator mark shown as an arrow 32 and provided along its lower edge spaced equally from the center point with a pair of notches 33. By means of the notches the plate 22' is adapted to be slipped down over and supported upon a pair of screws or similar studs 34 attached to the wall 35. The fingers or hooks 23' while the device is in the position shown in Fig. 13 serve the same purpose as described above in connection with the fingers or hooks 23 for forming the loops 21 of the necktie.

The improvement illustrated in the first sheet of the drawings calls for a collar specially made with the pairs of slots 12 and 14, but with the device of sheet 2 the ordinary collar having a locking tongue 11 may be used, and to form holes 12' in the tongue the operator has but to remove the jack from the screws 34, apply the plate portion thereof along the lower edge of the collar with the indicator 32 in vertical alinement with the buttonhole 13, and bring the points of the prongs 23' simultaneously in direct position to locate and make the holes 12'. 130

This operation is completed obviously by the operator employing the plate as a handle and forcing the prongs directly through the collar. No serious damage is done to the collar by this operation and the holes are formed not only at the proper points but in such a manner as to permit the shanks 28 of the attachment devices 27 to be projected directly inward therethrough while the pin 29 is in the position of Fig. 11. The shank is then turned at an angle so as to permit the pin to be projected into the position of Fig. 10 locking the device to the collar. The necktie loops 21 formed on hooks 23' on the jack will naturally be spaced according to the space between the two attachment devices 27. The operator then before fastening his collar will apply the necktie to the fasteners as previously explained, making it an easy expedient for him to attach the combined collar and necktie at the same time to his shirt.

I claim:

1. The combination with a collar having a locking tongue having openings formed on the locking tongue ply on opposite sides

of the collar buttonhole formed therein, of a necktie having laterally projecting members, and fastening means coöperating with said members and said openings of the collar, whereby the tie may be fastened in normal wearing form prior to the adjustment of the collar to the shirt, substantially as set forth. 30

2. In a device of the character set forth, 35 the combination of a pair of clips having straight shanks and open topped hooks for supporting a necktie, and a collar having a locking tongue ply having on opposite sides of its center pairs of vertically aligned holes 40 to detachably receive said shanks and thereby hold and support in fixed position said clips.

3. The herein described means for attaching a previously knotted tie in combination with a collar to a shirt, the same comprising tie holding means carried by the collar on opposite sides of the buttonhole, and to which the tie may be secured at both of said sides previous to placing of the collar around the neck of a person. 45 50

JOSE RICARDO ELIZONDO.
